UNITED STATES PATENT OFFICE

2,538,440

CULINARY IMPLEMENT

Malcolm H. Bell, New York, N. Y.

Application May 13, 1947, Serial No. 747,647

5 Claims. (Cl. 99—394)

1

This invention relates to culinary implements, and more particularly to a device intended primarily for cooking foods, such as steaks, sausages, and the like over an open fire.

The principal object of the present invention is the provision of a novel, inexpensive, and efficient device for grasping and supporting an article to be cooked, such article being supported at the desired distance above the coals and in proper angular relation thereto, without particular attention on the part of the person performing the operation. More specifically, it is an object of this invention to provide a culinary device comprising a vertical supporting member, a generally horizontal member rotatably mounted at or adjacent the top of the supporting member, and provided with means for securing the article to be cooked, and means for maintaining such securing means in the desired angular relation to the surface of the coals, such means for example comprising a weight supported on the end of the horizontal member opposite to the said food securing means.

A further object is the provision of a device of the character described, in which the vertical angle between the vertical member and the generally horizontal member may be adjusted to vary the distance of the food securing means from the burning coals, and whereby the vertical member and the normally horizontal member may be brought into parallelism for purposes of storing or carrying the device.

Other and further objects, features and advantages will be apparent from the description which follows, read in connection with the accompanying drawings in which:

Figure 1 is a perspective view of a culinary implement constructed in accordance with the present invention;

Figure 2 is a partial side elevation of the device of Figure 1;

Figure 3 is a partial plan view of the device of Figure 1;

Figure 4 is a side elevation of a modified form of the invention; and

Figure 5 is an enlarged detail view of the adjusting means employed in the device of Figure 4.

In order to facilitate an understanding of the invention, reference is made to the embodiments thereof shown in the accompanying drawings, and detailed descriptive language is employed. It will nevertheless be understood that no limitation of the invention is thereby intended and that various changes and alterations are contemplated such as would ordinarily occur to one

2

skilled in the art to which the invention relates.

Referring to Figures 1, 2 and 3, the device there illustrated, which is preferably made of metal rod stock or heavy wire, comprises generally a vertical member or stake 10, which may be pointed at its lower end, and which is provided at its upper end with a helically formed horizontal extension 11 which comprises, in effect, a bearing member, and a generally horizontal member 12 rotatably supported in the bearing 11. The member 12 is provided at one end with a series of U-shaped loops 13 terminating in a final transverse portion 13', and is also provided between its point of support on the stake 10 and the first U-shaped loop 13 with a convolution forming an eye 14. At its end opposite the loops 13, the horizontal member 12 is formed to provide an eye 15 which lies in the plane of the loops 13 or in a parallel plane.

For the purpose of securing an article to be cooked against the grid formed by the loops 13, a length of heavy wire or similar material is formed to provide a series of loops 16 similar to the loops 13 and terminating in a transverse portion 16' which is pivotally connected with the portion 13' by means of links 17. The upper grid formed by the loops 16 is provided with a portion 18 extending parallel to the member 12 and terminating substantially above the eye 14 of the member 12, the extremity of the portion 18 being bent upwardly to a slight extent. A link 19 permanently secured within the eye 14, is employed for securing the upper grid against the article to be cooked, the link 19 being hooked over the portion 18 of the upper grid for this purpose, after the article is in place, as illustrated in Figure 2.

In order that the article to be cooked, such as a steak secured between the upper and lower grids just described, may be maintained parallel to the surface of the coals, a dumbbell-shaped weight 20 is slidably mounted within the eye 15. It will be readily apparent that when the steak or other article is arranged parallel to the ground, i. e., to the surface of the burning coals, it will be maintained in this position by virtue of the weight 20, until the horizontal member and its associated parts are rotated through 180° to present the opposite end of the article to the fire, when the weight will slide through the eye 15 and will serve the same function as before.

In the form of the invention illustrated in Figure 4, the vertical member 10' is formed in two portions 21 and 22. The lower portion 21 is provided at its upper end with a circular member

23 having one of its faces serrated or toothed while the upper portion 22 of the member 10' is provided at its lower end with a member 24 which is complementary to the member 23. The two members 23 and 24 may be secured together in any desired relation by means of a bolt 25 and wing nut 26, the end of the bolt being peened or otherwise upset as at 27 to prevent the wing nut from being removed and thus preventing its loss.

As will readily be understood, the vertical angle between the horizontal member 12' and the vertical member 10' may be adjusted by loosening the wing nut 26 and rotating the members 23 and 24 relative to each other and, for purposes of storing or carrying the device, the vertical member 10' may be brought into parallelism with the member 12' as illustrated in dotted lines in Figure 4. In other respects, the device of Figures 4 and 5 is identical with that of Figures 1, 2 and 3.

Obviously, the vertical member 10 need not be driven into the ground in order to support the device, but other means such as a heavy base secured to the lower end of the vertical member, may be employed for this purpose. Likewise, the details of the food securing means may be varied, and other modifications may be employed without departing from the scope of the invention.

Having thus described the invention, what is claimed as new and desired to be secured by Letters Patent is:

1. A culinary implement comprising a vertical supporting member, a generally horizontal member mounted adjacent the upper end of said vertical member for rotation about its own axis, means associated with said horizontal member for securing thereto an article to be cooked, and means associated with said horizontal member for maintaining said securing means in a substantially horizontal plane, said last means comprising a weight loosely mounted on and extending transversely of said horizontal member, and adapted to move from one side to the other of said horizontal member when the latter is rotated through 180°.

2. A barbecue device comprising a stake surrounded by a horizontal sleeve, a pair of hinged grids adapted to clamp between them the food

to be cooked, an elongated handle extending from one of the grid elements through the sleeve on the stake and rotatable therein and terminating in a ring whose plane approximately coincides with the plane of the first element of the grid, and a dumbbell-shaped weight whose shaft is encircled loosely by said ring, said weight being so mounted as to move from one side to the other of said handle when the latter is rotated through 180°.

3. A device according to claim 1, including a variable joint in said vertical member near the upper end thereof, for adjusting the angle of said upper end and said horizontal member relative to the lower end of said vertical member.

4. A device according to claim 1, including a variable joint in said vertical member near the upper end thereof, for adjusting the angle of said upper end and said horizontal member relative to the lower end of said vertical member, said joint being formed and arranged to permit said vertical and horizontal members to be placed in parallelism for purposes of storing and carrying said implement.

5. The device of claim 1, the mounting for said horizontal member being formed by a helically bent horizontal extension of said vertical member.
